UNITED STATES PATENT OFFICE.

EDWARD B. RODGERS, OF NEW YORK, N. Y.

VALVE CONSTRUCTION FOR GAS ENGINES.

Refiled for abandoned application Serial No. 535,327, filed February 9, 1922. This application filed December 8, 1925. Serial No. 74,182.

This invention has relation to internal combustion engines and has for an object to provide a novel arrangement of intake and exhaust valves whereby to accomplish the partial cooling of the exhaust valves by the admission of intake gases which are permitted to impinge upon a point located intermediate a pair of exhaust valves, thus cooling both of said valves simultaneously. 5
10 Another object of the invention is to provide improvements in internal combustion engines and more particularly such engines of the four cylinders, air cooled type wherein in a pair of exhaust valves are provided for each cylinder to permit the exhaustion of burnt gases, said exhaustion being withdrawn from the cylinder in a lateral direction, and wherein an intake valve is provided and located between the exhaust 15 valves and directly thereabove whereby intake gases will impinge upon a point of the cylinder head between the exhaust valves to thus partially cool both of said valves simultaneously during such action and thereby 20 increase the general efficiency and durability of the engine.

In addition to the foregoing this invention comprehends improvements in the details of construction and arrangement on parts to be hereinafter described and particularly set forth in the appended claims.

In the accompanying drawings in which similar and corresponding parts are designated by the same characters of reference 35 throughout the several views in which they appear—

Figure 1 is a view in vertical, longitudinal section taken through the cylinder head and valve chambers of an internal combustion engine constructed in accordance with my invention, and

Figure 2 is a view thereof in vertical transverse section taken on the lines 2—2 of Figure 1.

With reference to the drawings, 10 indicates the upper end of a cylinder head and 11 a combined intake and exhaust chamber communicating laterally with the upper end of the cylinder through the medium of the 45 passage 12. An enlargement 13 is formed with the cylinder at one side and is provided with a pair of exhaust ports 14 which extend upward at an angle and communicate with the chamber 11. A pair of openings 15 are drilled in the enlargement 13,

one in each port 14 to receive a vertical bushing 16, each bushing serving as a guide for a valve stem 17 of which a pair are provided. Formed upon the upper end of each valve stem is a conventional form of ground disk valve 18 which bear upon valve seats formed at the juncture of the chamber 11 and the exhaust ports. It will be noted that these valves 18 are in spaced relation as shown in Figure 1 and that a point has 50 been indicated by the letter B upon the floor of the chamber 11 exactly midway between the centers of the said valves. A rectangular opening 19 is formed in the cylinder head or in the top wall of the chamber 11 to receive a casting or cap 20 which is provided with the flange 21 to rest upon and secured to the cylinder head by suitable screws or expansion bolts being removed from the chamber 11. Said cap 20 is provided with an angular intake port 22 which communicates with the chamber 11 and a valve seat 23 is formed at the juncture of said intake port and the chamber 11. A vertical opening 24 is formed in the cap 55 to receive a bushing 25, the latter serving to slidably support a valve stem 26. It will be noted that the vertical center of said valve stem is located, when viewed in Figure 1 directly over the point B or intermediate 60 the exhaust valves and when viewed in Figure 2 is seen to be offset slightly from the center line between the exhaust valves and toward the cylinder bore. A disk valve 27 is formed upon the lower end of the valve 65 stem 26 and controls the intake port. A cylindrical extension 28 is formed upon the cap and is hollow to form a cavity through which the stem 26 extends. A washer 29 is secured to the upper end of said valve stem 70 and lies flush with the upper edge of the extension 28. A coil spring 30 is interposed between the floor of said cavity and the washer 29 and embraces the valve stem to normally retain the valve 27 in seated position. In a similar manner coil springs 31 75 are embraced about the lower ends of the valve stem 17 and bear at one end against the casting 13 and at their opposite ends against grooved conical washers 32 which receive 80 the lower ends of the valve stems and which are held in position by reason of the conical members 33 which are threadedly or otherwise secured to the lower ends of the valve stems and against which the inner sides of 85

said washers bear. It will be observed that the sides of the cylinder, the casting 13 and the cap 20 are plentifully supplied with integral flanges and projections 34 for the purpose of promoting the radiation of heat from the engine and to thus ensure the maintenance of a low temperature of the engine during operation.

Upon each intake stroke of the piston the valve 27 will automatically open against the tension of the spring 30 and permit a charge of cool combustible vapor to enter the chamber 11 with considerable velocity. The stream of vapor will thus be directed downward upon both of the exhaust valves 18 and upon the point B of the chamber wall thus acting to cool said exhaust valves and chamber walls and at the same time preheat the charge before its entrance into the cylinder for subsequent ignition. Owing to the combined area of the exhaust ports a rapid discharge of the exhaust gases is ensured with a minimum of back pressure. Also it will be obvious that inasmuch as the exhaust valves are thus swept and cooled by the incoming vapor the formation of carbon upon and around the exhaust valves is prevented to a considerable extent. Access to the exhaust valves for regrinding is readily permitted by the removal of the cap 20. It will also be noted that the spring mechanism for the intake valve is almost entirely enclosed within the extension 28 and in this manner injury to the parts is prevented by the accidental striking of objects against the valve spring or valve stem. Many other conveniences and advantages are presented by the novel construction of my improved engine and the arrangement of its parts which will be readily apparent to those skilled in the art to which this invention appertains.

While I have illustrated and described my invention with some degree of particularity,

I realize that in practice various alterations therein may be made, I therefore reserve the right and privilege of changing the form of the details of construction or otherwise altering the construction without departing from the spirit of the invention or the scope of the appended claims.

Having thus described my invention what I claim as new and desire to secure by United States Letters Patent is:—

1. In an internal combustion engine, the combination of a cylinder, a cylinder head having a chamber disposed laterally at one end of the cylinder and in communication therewith, the bottom wall of said chamber having a pair of valve seated openings, said cylinder head having a relatively large opening opposite said valve seated openings, an integral extension of the cylinder having a pair of exhaust ports one for each of said valve seated openings, a valve for each of said openings, spring head stems for said valves, a cap to be received in the second mentioned opening and having a valve seated opening disposed between the first mentioned openings and in opposition thereto, 70 said cap having an intake port, a valve for said last mentioned valve seated opening, and a spring press stem for said valve.

2. In an internal-combustion engine, a cylinder, a lateral extending chamber carried by and communicating with the bore of the cylinder, a plurality of vertically disposed exhaust valves arranged in the bottom of the chamber and a single intake valve arranged in the chamber above and directly intermediate the exhaust valves, whereby the incoming mixture controlled by the intake valve will impinge upon the exhaust valves and the adjacent cylinder wall to cool said valves and wall.

In testimony whereof I affix my signature.

EDWARD B. RODGERS. [L.S.]
